UNITED STATES PATENT OFFICE.

JULIUS GRUNEWALD AND PAUL GAUGER, OF CHICAGO, ILLINOIS.

DESIGN FOR A CAP.

SPECIFICATION forming part of Design No. 22,520, dated June 13, 1893.

Application filed February 10, 1893. Serial No. 461,838. Term of patent 3½ years.

To all whom it may concern:

Be it known that we, JULIUS GRUNEWALD and PAUL GAUGER, citizens of the United States, residing at Chicago, in the county of 5 Cook and State of Illinois, have invented and produced a new and original Design for Caps, of which the following is a full, clear, and exact specification, reference being had to the accompanying drawings, forming a part thereof.

10 In the said drawings, Figure 1 is a perspective view of a cap showing our design, and Fig. 2 is a side elevation thereof.

The leading features of our design will be hereinafter pointed out in the claim.

15 The crown A of the cap is dome shaped and the lower edges of the flaps or portions B, C, join with the lower edge of the crown and roll upward and outward as a continuation thereof. The portions B, C, are separated or divided by V shaped notches as shown, whose lower ends or points are somewhat rounded and terminate a considerable distance above the lower edge of the cap. These V shaped notches are situated nearer the front than the

20 back of the cap so as to make the front portion B of less length than the back portion C, which latter extends around the back of the cap and terminates at the front in two high points G, which are higher than the adjacent

ends of the portion B. The ends of the portion B are formed on an obtuse angle and such portion at its mid-length is provided at its upper edge with a peak II. The upper edges of the portions B, C, are provided with a continuous hem or border as shown, formed of a 30 contrasting shade of material.

Having thus described our design, what we claim, and desire to secure by Letters Patent, is—

A design for caps consisting of the dome 40 shaped crown A, up-turned overhanging flaps B, C, separated by V shaped notches rounded at their lower ends and terminating at a distance above the lower edge of the cap, the high peak II on the front flap B, and the high 45 corners G on the forward ends of each of the flaps C, and said corners being higher than the corners of the flap B and the rear portions of the flaps C, and the continuous border extending around the upper edges of said flaps and 50 the V shaped notches, substantially as shown and described.

JULIUS GRUNEWALD.
PAUL GAUGER.
